TERMINAL BUSHINGS

Charles F. Sonnenberg, Penn Hills Township, Allegheny County, Pa., assignor to Westinghouse Electric Corporation, East Pittsburgh, Pa., a corporation of Pennsylvania

Filed July 23, 1959, Ser. No. 829,091
5 Claims. (Cl. 174—142)

This invention relates, generally, to terminal or entrance bushings and, more particularly to bushings of cast resin.

The fundamental purpose of an entrance bushing in electrical apparatus is to allow passage of a current conductor at some voltage above ground through a grounded tank or container. Since the tank top is usually a relatively thin sheet of steel, the voltage stress is concentrated on a small section of the bushing surface, much like a razor edge attempting to cut it.

Bushings with metal foils were developed utilizing a condenser effect, and foilless bushings have been provided with a metallic mounting flange brazed to a metallic cylinder which was pressed onto the bushing. Both of these methods have satisfactorily distributed the voltage stress over a greater surface area.

Terminal bushings of cast epoxy resin have been considered by apparatus manufacturers, both domestic and foreign, for several years. The method most often advanced has been to mold the bushing in a single casting to include the condenser, weather casing and mounting flange. However, there are certain objections to a bushing constructed in the foregoing manner, particularly when it is to be utilized in outdoor service. The surface is subjected to erosion and it is difficult to produce a cast surface which is as glossy and smooth, and, thus, as self cleaning as glazed porcelain of which the weather casing has been composed previously.

An object of this invention is to provide a cast resin bushing having a protective weather casing composed of porcelain, glass or the like.

Another object of the invention is to provide a cast resin bushing having an integrally bonded metallic mounting flange and metallic cylinder.

A further object of the invention is to provide a cast resin bushing having a metallic cylinder which is utilized as an outer ground foil and as a portion of the mold for casting the resin.

Still another object of the invention is to provide a cast resin bushing having a metallic screen embedded within the molded material.

A further object of the invention is to utilize a porcelain casing as part of the mold for a cast resin bushing.

A still further object of the invention is to assure a voidless bond between the porcelain casing and the molded portion of a bushing.

Other objects of the invention will be explained fully hereinafter or will be apparent to those skilled in the art.

In accordance with one embodiment of the invention, a cast resin bushing is formed by securing one end of a cylindrical metal sleeve to one side of a mounting flange and utilizing the sleeve as part of a mold for casting the bushing. The inside of a porcelain casing is lined with a flexible, elastic material and the casing is disposed on the other side of the mounting flange and utilized as another part of the mold. A removable mold is provided at the other end of the metal sleeve. Thus, the casing and the metal sleeve are bonded to the cast resin to form the bushing.

For a better understanding of the nature and objects of the invention, reference may be had to the following detailed description, taken in conjunction with the accompanying drawing, in which:

2

FIGURE 1 is a view, in section, of a cast bushing embodying features of the invention with the casting molds in position;

5 FIG. 2 is a view, partly in section and partly in elevation, of the bushing shown in FIG. 1, the molds being removed;

10 FIGS. 3 and 4 are views, similar to FIGS. 1 and 2, respectively, of another embodiment of the invention, and

15 FIG. 5 is a view, partly in section and partly in elevation of still another embodiment of the invention.

20 Referring to the drawing, and particularly to FIGS. 1 and 2, the terminal bushing shown therein comprises a cylindrical metal sleeve 10, which is secured to a metal mounting flange 11, a conductor 12, which extends longitudinally through the sleeve 10 and is spaced from the sleeve, a thermoset resin body 13 and a cylindrical metal screen 14 which is embedded in the resin body 13 concentrically with the conductor 12. The sleeve 10 and mounting flange 11 are preferably composed of aluminum since aluminum has substantially the same thermal coefficient of expansion as the thermoset resin material utilized in casting the body. If a resin having a different coefficient of expansion is utilized, the sleeve 10 should be composed of a metal, such as copper, having substantially the same coefficient of expansion. As shown, the sleeve 10 is welded to the flange 11. However, the sleeve and the flange may be formed as one piece.

25 A removable mold 15 is provided at the lower end of the sleeve 10. Another removable mold 16 is provided on the upper surface of the flange 11. The mold 16 may be retained in position by attaching a cap 17 to the upper end of the conductor 12.

30 The thermoset resin utilized for the body 13 should be one that has good physical strength, has a relatively low shrinkage during curing and has good adherence to metal and ceramics, such as porcelain and glass. The resinous polymeric epoxides, such as a thermosetting resin comprising a glycidyl polyether of a polyhydric phenol having a 1,2-epoxy equivalence of between 1 and 2, have been found to meet the foregoing requirements and have been successfully utilized in making bushings of the present type. Such epoxide resins are described in U.S. Patents 2,728,744 and 2,739,134.

35 As previously explained, the metal sleeve 10 and the grounding flange 11 are provided to distribute the voltage stress over a greater surface area. In the present structure, the sleeve 10 is utilized as part of the mold for casting the resin. As described in a copending application of R. G. Black, Serial No. 828,991, filed July 23, 1959, the sleeve 40 10 may be provided with a plurality of longitudinal slots 18 as shown in FIG. 2. The slots 18 permit the adhesion of the resin to the metal to pull the segments of the metal shell inwardly during the curing process, thereby preventing shrinkage of the resin from forming voids between the 45 metal shell and the resin. When the bushing is utilized for relatively high voltage service, any voids between the resin and the metal may give rise to the phenomenon of internal corona causing radio interference. When the slots 18 are provided in the metal sleeve 10 a rubber 50 sleeve or other temporary means, such as aluminum foil, may be provided around the sleeve 10 to retain the resin within the sleeve during the casting process.

55 When the metal sleeve 14 is embedded in the resin body, as shown in FIGS. 1 and 2, the outer cylinder 10 functions as an outer foil, thereby obtaining a condenser effect similar to that obtained in other condenser bushings. The sleeve 14 is preferably an aluminum screen. A screen is utilized instead of foil because it has sufficient strength to support its own weight and thus stand without 60 collapsing in the resin while it is curing. Also, the many perforations in the screen permit the resin to bond completely through the screen. Thus, any relaxing caused by

difference in thermal coefficient of expansion will not permit the resin body to relax itself from the screen and form internal voids. As previously stated, aluminum has substantially the same thermal coefficient of expansion as the thermoset resin utilized in the present bushing.

While the resin may be poured into either one of the molds, the molds are preferably turned upside down and the resin poured into the mold 15 during the casting process. After the resin is cured, the molds 15 and 16 may be removed, thereby providing the bushing, shown in FIG. 2. This bushing is suitable for indoor service. The flange 11 may be attached to a tank or container for electrical apparatus by bolts inserted in the holes 19.

As previously explained, it is desirable to provide a porcelain casing for the exposed portion of a bushing when the bushing is utilized for outdoor service. As shown in FIG. 3, a porcelain casing 21 may be utilized as part of the mold for casting the resin body 13. However, in order to prevent voids from forming between the resin body 13 and the casing 21 during the curing process, the casing is lined with a flexible and elastic material 22. The lining 22 may be a silicone rubber or a neoprene-base rubber cement.

The casing 21 may be retained in position on the flange 11 by a terminal cap 23 which is attached to the upper end of the conductor 12. As previously explained, the sleeve 10 is preferably provided with a plurality of longitudinal slots 18 and a temporary means is provided on the sleeve 10 to prevent the resin from coming out through the slots 18 during the casting process. After the resin is cured the mold 15 may be removed, thereby providing the bushing shown in FIG. 4 having the casing 21 and the sleeve 10 bonded to the resin body. The electrical connections may be made to the lower end of the conductor 12 and to the terminal cap 23. The mounting flange 11 may be attached to the cover of a tank or container in the manner previously described.

If it is not desired to utilize the casing 21 as part of the mold during the casting process, the resin body may be cast in the manner previously described with reference to FIGS. 1 and 2. The elastic liner 22 may be formed into a double flanged frustum of a right circular cone. The inside diameter of the cone would be slightly less than the outside diameter of the cast resin body portion of the bushing and the outside diameter would be slightly greater than the inside diameter of the porcelain casing. The elastic cone would be pressed over the molded bushing with the lower flanged surface acting as a gasket between the porcelain casing and the mounting flange. After the porcelain is firmly pressed into place over the elastic cone the terminal cap is screwed down providing the compressive force necessary to keep the porcelain in place. The upper flanged surface on the elastic cone acts as a gasket between the terminal cap and the porcelain.

In the modification of the invention shown in FIG. 5, a mounting flange 11' is formed as an integral part of the cast resin bushing body 13'. The flange 11' is attached to a tank cover or wall 24 by means of bolts 20. In this manner it is not necessary to provide a metal mounting flange as in the bushings previously described.

In order to distribute the voltage stress over a greater area, a metal screen or disc 25 is embedded in the flange 11'. The disc 25 is connected to metal washers or inserts 26 disposed in the holes for the mounting bolts 20. The disc 25 is connected to a cylindrical metal screen 27 which is embedded in the resin body 13' concentrically with the conductor 12. Thus, when the bushing is attached to a grounded tank the screen 27 is grounded through the disc 25, the washers 26 and the mounting bolts 20, thereby distributing the voltage stress.

It should be noted that the metal sleeve 10 is not attached to the tank cover 24 since the sleeve 10 is a part of the bushing structure and is removable with the bushing. If it is not desired to utilize the sleeve 10 as a part of the mold for casting the bushing the sleeve 10 may be

omitted from the present structure since the voltage stress is distributed by the metal screen 27 in the manner previously described.

From the foregoing description it is apparent that the present invention provides a bushing which may be cast from a thermoset resin. Such a bushing is suitable for indoor service. If it is desired to utilize the bushing for outdoor service a ceramic weather casing may be provided on the exposed portion of the bushing. Bushings constructed in accordance with the present invention have been found to have less radio interference than bushings of prior construction.

Since numerous changes may be made in the above-described construction, and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. In an insulating bushing, in combination, a cylindrical metal sleeve having a metal flange secured thereto, said sleeve having a plurality of elongated longitudinal slots therein, a conductor extending longitudinally through and spaced from the sleeve, a thermoset epoxide resin body filling the space between the conductor and the sleeve and adhering to the inside of the sleeve, said slots permitting the sleeve to contract with the resin body, said resin body extending beyond the ends of the sleeve, and said conductor extending beyond the ends of said resin body.

2. In an insulating bushing, in combination, a cylindrical metal sleeve having a metal flange secured thereto, said sleeve having a plurality of elongated slots around its periphery a conductor extending longitudinally through and spaced from the sleeve, a thermoset resin body filling the space between the conductor and the sleeve and adhering to the inside of the sleeve, said slots permitting the sleeve to contract with the resin body, a cylindrical metal screen embedded in the resin body concentrically with the conductor, said resin body extending beyond the ends of the sleeve, and said conductor extending beyond the ends of said resin body.

3. In an insulating bushing, in combination, a cylindrical metal sleeve having a metal flange secured thereto, said sleeve having a plurality of elongated longitudinal slots therein, a conductor extending longitudinally through and spaced from the sleeve, a thermoset resin body filling the space between the conductor and the sleeve and adhering to the inside of the sleeve, said slots permitting the sleeve to contract with the resin body, said resin body extending beyond the ends of the sleeve, said conductor extending beyond the ends of said resin body, and a porcelain casning disposed on said resin body above said flange.

4. In an insulating bushing, in combination, a cylindrical metal sleeve having a metal flange secured thereto, a conductor extending longitudinally through and spaced from the sleeve, a thermoset resin body filling the space between the conductor and the sleeve and adhering to the inside of the sleeve, said resin body extending beyond the ends of the sleeve, said conductor extending beyond the ends of said resin body, a ceramic casing disposed on said resin body above said flange, and a self-retaining flexible and elastic material interposed between the casing and the resin body.

5. In an insulating bushing, in combination, a cylindrical metal sleeve having a metal flange secured thereto, said sleeve having a plurality of elongated longitudinal slots therein, a conductor extending longitudinally through and spaced from the sleeve, a thermoset resin body filling the space between the conductor and the sleeve and adhering to the inside of the sleeve, said slots permitting the sleeve to contract with the resin body, said resin body extending beyond the ends of the sleeve, said conductor extending beyond the ends of said resin body, a porcelain

casing disposed on said resin body above said flange, and said casing being lined with a self-retaining flexible and resilient material interposed between the casing and the resin body.
